UNITED STATES PATENT OFFICE.

HARRY W. MITCHELL, OF CLEVELAND, OHIO, ASSIGNOR TO G. F. MITCHELL & SON, A PARTNERSHIP CONSISTING OF GEORGE F. MITCHELL, GEORGE R. MITCHELL, AND HARRY W. MITCHELL, OF CLEVELAND, OHIO.

WASHING MACHINE.

Application filed July 18, 1924. Serial No. 726,857.

This invention relates to washing machines for household laundry work of the type in which a rotary fluid tight cylinder forms the container for the cleansing liquid as well as for the material to be cleansed, the present invention being an improvement upon the machine disclosed in my co-pending application Serial No. 709,402, filed April 28, 1924.

10 The application above referred to provides means for automatically relieving the cylinder of internal gas pressure during the operation thereof, this being accomplished by means of a pressure relief valve which is automatically operated during each revolution of the drum to permit escape of gases therefrom.

It has been found that small quantities of liquids will at times escape through the relief valve due to an excessive quantity of suds within the drum.

25 It is the object of the present invention to provide means for collecting any such liquid which may escape through the relief valve and prevent the dripping of such liquid from the head of the drum to the floor.

The following description and accompanying drawings set forth in detail certain 30 means embodying the invention, the disclosed means, however, constituting but one of the various mechanical forms in which the principle of the invention may be employed.

35 Reference should be had to the accompanying drawings forming a part of this specification in which Fig. 1 is a side elevation of a washing machine embodying the invention; Fig. 2 is a fragmentary view 40 showing an axial section through the relief valve; Fig. 3 shows the relief valve in elevation.

45 Referring to the accompanying drawings, the washing machine consists of a suitable supporting frame 1 in which is mounted a horizontally disposed drum 2 which is supported at both ends in the frame by means of trunnions 3 and 4, the drum being operated through suitable gearing in the gear 50 casing 5. The drum 2 is fluid tight and forms a container for the cleansing liquid and also for the articles being washed. On the inner side of the cylindrical wall of the drum a series of air trapping chambers are

formed by arcuate perforated partition 55 plates 6. The drum will be supplied with sufficient liquid to bring the level of the liquid to substantially the axis of the drum and during rotation of the drum the peripheral air chambers become filled with water 60 while passing through the liquid and discharge the water during their passage above the surface of the liquid. The perforations in the plates 6 are so proportioned and distributed that the chambers are completely 65 filled with water during passage through the liquid and completely discharge the water and become filled with air during their passage above the level of the liquid while their passage beneath the level of the 70 liquid displaces the air therein causing the air to bubble up through the liquid and articles of clothing in the liquid and during the passage of the chambers above the surface of the liquid the streams of liquid are discharged downwardly from the chambers. The currents of air rising from the air 75 chambers through the liquid tend to force the material in the liquid upwardly and this upward movement is counteracted by the 80 streams of water flowing by gravity from the chambers above the surface of the liquid. The fabric materials in the liquid are thus held in suspension in the liquid and thoroughly cleansed by the streams of air and 85 liquid to which they are subjected. The cylindrical wall of the drum is provided with a detachable lid 7 by means of which access may be had to the interior thereof.

One of the heads or end walls of the drum 90 has attached thereto a valve casing 8 which opens to the interior of the drum, the valve 8 being provided with a conical valve seat 9 upon its inner end. The casing 8 carries a valve 10 which engages the seat 9 and closes 95 the opening into the drum, the valve 10 being provided with a stem 11 which extends through a boss 12 in the outer wall of the casing 8 which is provided with a gland 13 to prevent escape of liquid. The valve 10 is normally held against its seat by means of a coil spring 14 which is interposed between the casing 8 and a pin 15 adjacent the outer end of the valve stem. Fixed to the frame adjacent the head of the drum 100 in which the valve is mounted is a cam 16 which is engaged by the stem 11 of the valve 10 while the valve is passing above the axis 105

of the drum. The cam 16 serves to automatically open the valve during each revolution of the drum to allow escape of gases therefrom thereby preventing excessive pressure within the drum.

5 A drain pipe 17 is connected to the casing 8 outside the head of the drum and extends inwardly therefrom toward the axis of the drum, the inner discharge end 18 of the 10 drain pipe 17 being bent outwardly from the head of the drum. The discharge end 18 of the drain pipe projects into an annular collecting member 19 which is fixed to the frame adjacent the head of the drum. The 15 annular collecting member 19 is mounted in a vertical position and coaxially with respect to the axis of the drum. The collecting member 19 is formed with inner and outer oppositely facing channels 20 and 21 projecting 20 inwardly toward the head of the drum, the inner annular channel 20 surrounding the trunnion therein and facing outwardly and the outer channel 21 being spaced outwardly from the inner channel 20 and facing 25 inwardly. The spaced channel members 20 and 21 provide between them an annular opening into which the discharge end 18 of the drain pipe projects. Liquid discharged from the drain pipe 17 against the outer side 30 of the collecting member or into the inner channel 20 and flows by gravity into the outer channel 21 which is wider than the inner channel 20. A drain pipe 22 extends from the lower portion of the collecting 35 channel 21 and extends to adjacent the bottom of the frame 1 so that liquid deposited in the collecting member 19 may be discharged into a suitable collecting receptacle beneath the machine.

40 Having described my invention, I claim:

1. A washing machine having a rotatably mounted substantially fluid tight drum forming a container for a body of cleansing liquid and articles to be cleansed, a pressure relief valve carried by the drum, means for operating the valve during rotation of the drum to permit escape of gases therefrom, and means associated with the valve for collecting any liquid escaping through the 45 valve.

50 2. A washing machine having a rotatably mounted substantially fluid tight drum forming a container for a body of cleansing liquid and articles to be cleansed, a pressure

55 relief valve carried by the drum, means for operating the valve during rotation of the drum to permit escape of gases from the interior thereof, a casing enclosing said valve upon the exterior of the drum, and means 60 for draining liquid from said casing.

3. A washing machine having a rotatably mounted substantially fluid tight drum forming a container for a body of cleansing liquid and articles to be cleansed, a relief valve in an end wall of the drum, means for operating the valve during rotation of the drum to permit escape of gases therefrom, a casing enclosing said valve upon the exterior of the drum, a drain pipe connected to said chamber, and a stationary annular collecting member into which said drain pipe discharges.

4. A washing machine having a frame in which is rotatably mounted a substantially fluid tight drum forming a container for a body of cleansing fluid and articles to be cleansed, said drum having a relief valve in an end wall thereof adapted to be opened to permit escape of gases therefrom, a casing enclosing the valve upon the outside of the drum, a drain pipe extending from said casing toward the axis of the drum, and a stationary collecting chamber fixed to the casing coaxially with the drum, said collecting chamber having a central opening 80 into which said drain pipe extends.

5. A washing machine having a frame in which is rotatably mounted a substantially fluid tight drum forming a container for a body of cleansing fluid and articles to be cleansed, said drum having a relief valve in an end wall thereof adapted to be opened to permit escape of gases from the drum, a casing enclosing said valve, a drain pipe extending from said casing toward the axis of 95 said drum, the inner outlet end of said pipe being bent outwardly from the drum, a collecting member fixed to the frame and having an annular inwardly facing outer channel and an annular outwardly facing channel within the outer channel between which channels the outlet end of the pipe extends, and a drain conduit connected to said fixed 100 collecting member.

In testimony whereof, I hereunto affix my 105 signature.

HARRY W. MITCHELL.
